UNITED STATES PATENT OFFICE.

GUSTAV BARTHEL, OF DRESDEN, GERMANY.

MECHANICAL PIANO-PLAYER.

SPECIFICATION forming part of Letters Patent No. 755,098, dated March 22, 1904.

Application filed March 31, 1903. Serial No. 150,430. (No model.)

To all whom it may concern:

Be it known that I, GUSTAV BARTHEL, a subject of the King of Saxony, residing at Dresden, Germany, have invented certain new and useful Improvements in Mechanical Piano-Players, of which the following is a specification.

My invention has reference to improvements in musical wind instruments, and relates more especially to improvements in key-actuating mechanical wind instruments known as "mechanical piano-players;" and the object of the invention is to provide simple but effective means for enabling the operator to accentuate certain passages more than others, shading thereby the tune-piece and giving it an individual emotional expression and artistic finish not obtainable with the constructions now in use.

I obtain the desired effect by interposing a special valve between the wind-chest and the channel leading to the small key-bellows for the purpose of being able to directly draw the air out of the small key-bellows by rapidly actuating the respective foot-pedal, causing a stronger sucking action than with the other bellows, which suck indirectly through the interposed wind-chest in the usual manner. This additional valve upon direct suction taking place automatically closes the inlet-port to the wind-chest.

In order to make the invention more readily understood, I have illustrated it on the accompanying sheet of drawings, Figure 1 of which represents a sectional view of the arrangement in the position of rest. Fig. 2 is a like section in the position when sucking through the wind-chest, and Fig. 3 is a similar sectional view of the parts when sucking directly from the small key-bellows.

a is the wind-chest, mounted on plate *b*, to the under side of which the sucking-bellows *d e* are secured by means of hinges *f* and which are connected to the foot-pedals by means of rods or the like *g*. The bellows of the wind-chest are held distended by springs *c*, and springs *i* tend to ordinarily contract the sucking-bellows *d e*. Each bellows has outlets *l*, with flap-valves *k*.

In the plate *b* are provided communication-ports *m*, having flap-valves *n o*. The valve *n* is adapted to open downwardly and the other valve *o* to open upwardly. Within the bellows *e* is provided a valve-casing *p*, which communicates by means of opening *r* with the passage *l*, leading to the small key-bellows. In the lower wall of this casing *p* is provided an aperture *v*, with flap-valve *t*.

The operation of the described mechanism is the following: If the bellows *e* is extended by pressing down the respective foot-pedal *h*, the air will be sucked directly out of the channel *s*, leading to the key-bellows, the valve *t* opening downwardly into the casing *p* and the valve *o* on plate *b* closing, as shown in Fig. 3. The more vigorously the foot-pedal is actuated, the more forcibly the air will be sucked out of the small key-bellows, causing the keys to strike correspondingly more forcibly. If the other foot-pedal is worked, the air is sucked out of the small key-bellows indirectly through the wind-chest *a*, the valves *n* and *o* opening in this case.

What I claim, and desire to secure by Letters Patent, is—

1. In a mechanical piano-player, the combination with the channel leading to the key-striking action, of a casing communicating therewith, a wind-chest communicating with said casing, a pair of sucking-bellows, one of said bellows communicating with said wind-chest, the other of said sucking-bellows communicating with said casing, said bellows being provided with suitable outlets, and means for operating the said bellows, substantially as specified.

2. In a mechanical piano-player, the combination with the channel of the key-striking action, a casing communicating therewith, a wind-chest communicating with said casing by a suitable port, a valve opening into said wind-chest provided for said port, a sucking-bellows communicating with said wind-chest by a suitable port, a valve opening into said sucking-bellows for said last-named port, a second sucking-bellows communicating with said casing by a suitable port, a valve opening into

said second sucking-bellows for said port between said second sucking-bellows and said casing, both of said bellows being provided with valved outlet-ports, and means for operating said sucking-bellows, substantially as specified.

In testimony that I claim the foregoing as

my invention I have signed my name in presence of two subscribing witnesses.

GUSTAV BARTHEL.
